Baldwin & Wright

UNITED STATES PATENT OFFICE.

WILLIAM HOWARD LIVENS, OF HAMPSTEAD, LONDON, ENGLAND.

PROJECTILE.

1,306,265.

Specification of Letters Patent. Patented June 10, 1919.

Application filed September 4, 1918. Serial No. 252,543.

To all whom it may concern:

Be it known that I, WILLIAM HOWARD LIVENS, a subject of the King of Great Britain, residing at Hampstead, London, England, have invented a new and useful Improvement in Projectiles, of which the following is a specification.

This invention relates to projectiles, particularly to those containing liquefied gas, and has for its object to allow the projectile to contain a large quantity of liquefied gas with respect to the quantity of material employed in the manufacture of the projectile.

According to this invention a projectile consists of a tube having contracted ends which are welded or otherwise suitably connected to a central tube.

In the accompanying drawings:—

Figure 1 is a sectional view of a projectile made in accordance with my invention, adapted to contain lethal liquefied gas.

Fig. 2 is a view on an enlarged scale and in section, showing more in detail the preferred construction.

25 *k* is a projectile or bomb formed of a tube having contracted ends welded to a central tube *l* which forms a stay. *n* is a diaphragm dividing the tube into two chambers.

The short chamber at the base end is fitted 30 with a screw plug *s* and has cross holes *m*, by which the liquid gas is introduced into the bomb; the longer end is packed with the bursting charge and takes the gaine *o* and the fuse *p*. The central tube welded at both 35 ends into the light body so strengthens it that a large content is obtained for a given size of projectile, and the weight of the lethal substance is proportionately increased so that it may even equal that of the empty

bomb. In this manner for a given number 40 of tons of gas projected, there is a very great saving in the quantity of material required over older devices.

In Fig. 2 parts similar to those shown in Fig. 1 are similarly lettered, but this figure 45 of the drawings shows more in detail the bursting charge, etc. In the construction shown, the pellet 1 carries the striking pin and is slidable in the bored body 2, being normally held at safety by a shear wire 3; 4 50 is a 0.410 revolver cartridge carrying the Bickford time fuse 5. The lower portion of the fuse comprises an elongated tube 6 carrying the detonator 7 containing the fulminate, the whole being carried in a sheath 8. 55

The operation of the fuse is as follows:—

Upon discharge of the projectile from the gun the pellet 1 sets back first shearing the wire 3 and then striking the percussion cap of the cartridge 4 to light the fuse 5 which 60 fires the detonator 7 after the bomb has landed.

What I claim is:—

In a projectile, the combination with a tube having contracted ends, of a central 65 tube to which the said contracted ends are connected, a diaphragm dividing the tube into a rear chamber and a forward chamber, a hole in the tube connecting the rear chamber to the projectile, a plug for closing the 70 rear chamber, an explosive charge in the forward chamber, and a fuse closing the forward chamber.

In testimony that I claim the foregoing as my invention, I have signed my name this 75 31st day of July, 1918.

WILLIAM HOWARD LIVENS.
